UNITED STATES PATENT OFFICE.

EDWIN N. HOWE, OF FOREST, OHIO.

MEANS FOR PRINTING BACKGROUNDS.

SPECIFICATION forming part of Letters Patent No. 427,766, dated May 13, 1890.

Application filed August 21, 1889. Serial No. 321,489. (No model.)

To all whom it may concern:

Be it known that I, EDWIN N. HOWE, a citizen of the United States, residing at Forest, in the county of Hardin, State of Ohio, have 5 invented certain new and useful Improvements in Means for Printing Backgrounds, of which the following is a specification, reference being had therein to the accompanying drawings.

10 This invention relates to certain new and useful improvements pertaining to photography; and it has for its object the production of an improved photographic printing-film for printing the backgrounds, the novelty residing in the peculiarities of construction and the combinations, arrangement, and adaptation of parts, all as more fully herein-after described, shown in the drawings, and then particularly pointed out in the appended claims.

15 I aim to produce a novel design in photography—a representation of a partially-transparent design producing a transparent shadow, a sharp, well-defined, perfect shadow, which may be extended to form a double shadow, or, in fact, more than two shadows, as desired.

20 The accompanying drawings, which with the letters of reference marked thereon form a part of this specification, are deemed sufficient to illustrate my invention.

25 In said drawings, Figure 1 is a view illustrating one form of my improved background-plate. Fig. 2 is a like view of the same with opaque center. Fig. 3 is a vertical central section through the same.

30 In carrying out my invention I take a base A, of any suitable transparent material, such as glass, celluloid, or any analogous substance. I then fix upon this plate the design desired. This may be done in a variety of ways. I will mention some of them.

35 Drawings may be made of the desired design and copied in the form of a negative by the aid of photography or any lithographic, 40 photographure, or mechanical printing process; or I may make a drawing of the design on a plain white paper and trim out the same carefully to the outline of the design, making the center opaque preferably, blending at the 45 edges toward the edges of the design. I then make an exact duplicate or fac-simile of this design upon thinner paper—such as tissue-

paper—trimming as before to the outlines of the design, but do not render this opaque. The thinner design is then mounted upon a 55 clean clear glass of the proper size, and the thicker design then mounted upon the thin one, but so arranged that the outlines of the two shall not be coincident—that is, allowing the margin or outline of one to project beyond that of the other, as shown in Figs. 1 and 2, so as to produce the effect of a shadow. Of course when the design is produced by the other methods the same relative arrangement of parts—namely, the translucent and 60 less translucent designs arranged relatively to each other, as are the thick and thin paper above referred to—should be observed, the design in principle and effect being the same, no matter by what method it is produced. 70

With a plate of the character above described the picture is produced as follows: The portrait which is intended to form the central figure, and which in a completed picture will occupy the space designated by the 75 letter B in the drawings, Figs. 1 and 2, is made in the form of a vignette photographic print. Then lay the print face downward upon the design, being careful in the adjustment that the face of the person comes directly back of 80 the opaque part of the upper design upon the base. Then press the same in contact and expose to the light in the ordinary manner until the desired shade is attained. The upper design acts as a mask in protecting the 85 portrait, except the edges, which print enough to show the design and give the transparent effect, while the lower design represents the shadow or a transparent design. I may sometimes print the design and portrait all at one 90 printing, in which case the upper design is not rendered opaque, the central portion thereof (designated by the letter B) being translucent, as indicated in Fig. 1, and the negative a vignette placed in contact therewith and the whole exposed to the light and the picture printed in the usual manner.

95 While in the drawings I have chosen to show the design as that of a leaf, it is of course evident that this is but one of the numerous 100 designs that may be employed—such, for instance, as feathers, stars, flags, shields, or other characters—and I may produce the plates with these various designs and keep them in stock,

the person desiring to have his picture taken taking his choice of design for background.

In the drawings the letter C designates the thin design and D the outer or thicker one.

5 The design may be printed on the base from an engraved or other plate, or it may be printed on a translucent film and laid or placed upon the plate, neither design to be coincident with the outline of the other.

10 What I claim as new is—

1. A device for printing backgrounds, which consists of a transparent base having a translucent figure thereon and an interposed relatively more translucent and adjacently arranged duplicate of the first-mentioned figure, substantially as specified.

2. A device for printing backgrounds, which consists of a transparent base, a translucent design thereon, and an interposed more translucent similar design with a portion opaque, substantially as described.

3. A device for printing backgrounds, consisting of a transparent base, a translucent design mounted upon the base, and a less translucent design of similar character mounted upon the first-mentioned design in a slightly-different plane, whereby the effect of a shadow is produced, substantially as described. 25

4. A device for printing backgrounds, consisting of a transparent base, a translucent design on said base, a less translucent design, a substantial duplicate of the first, mounted thereon, but not coincident with the outline thereof, and having a substantially central portion rendered opaque, substantially as 30 shown and described.

In testimony whereof I affix my signature in presence of two witnesses.

EDWIN N. HOWE.
